UNITED STATES PATENT OFFICE.

WILLIAM C. H. WEFEL, OF DENVER, COLORADO, ASSIGNEE OF FORTY-NINE ONE-HUNDREDTHS TO SAMUEL E. WHITAKER, HERBERT D. BARTLETT, AND ALBERT S. WHITAKER, ALL OF DENVER, COLORADO.

ELECTRIC-ARC LAMP.

1,151,841.

Specification of Letters Patent. Patented Aug. 31, 1915.

Application filed May 13, 1912. Serial No. 697,652.

To all whom it may concern:

Be it known that I, WILLIAM C. H. WEFEL, a citizen of the United States, residing at Denver, in the county of Denver and State of Colorado, have invented certain new and useful Improvements in Electric-Arc Lamps, of which the following is a specification.

This invention relates to new and useful improvements in electric arc lamps and its principal object resides in the provision of a regulating mechanism composed of an association of simple mechanical and electrical devices by means of which the electrodes are automatically re-adjusted to their proper distance when the interval between them becomes too long for the production of a steady flame but before it has increased to an extent too great for the passage of the current from one electrode to the other.

Other objects of my invention reside in the novel arrangement of the parts and in details of construction, all of which will be fully described in the following specification, reference being had to the accompanying drawings in the several views of which like parts are similarly designated, and in which,

Figure 1 represents a vertical section through the lamp casing showing the regulating appliance in elevation, Fig. 2, a vertical section through the lamp taken along the line 2—2, Fig. 1, Fig. 3, an enlarged sectional view of the casing in which the voltaic arc is produced, and adjacent parts of the lamp, Fig. 4, an enlarged view of the ends of the carbons, and adjacent parts of the regulating mechanism, Fig. 5 an enlarged view of the ends of the carbons and the adjacent parts of the regulating mechanism in the position they normally occupy during the period of illumination, Fig. 6, a plan view of the parts shown in Fig. 4, Fig. 7, a section taken along the line 7—7, Fig. 4, Fig. 8, a section taken along the line 8—8, Fig. 5, and Fig. 9, a section taken along the line 9—9, Fig. 3.

Referring more specifically to the drawings, the numeral 2 designates the cylindrical shell of a lantern in which the lamp is installed and which in the form shown in the drawings, is pivotally mounted upon a suitable base 3. The shell 2 has at one of its sides and at its top openings for the emission of light in a horizontal and a verti-

cal direction, which are covered by means of 55 lenses 4 and 5. The light passing through the upper lens 5 is concentrated by means of an inwardly projecting funnel 6 provided with an adjustable shutter 7 by means of which the passage of light from the lamp 80 to the lens may be obstructed.

The electrodes 8 of the arc-lamp are placed convergently in sleeves 9 secured in tubular holders 12 which extend outwardly from the circumferential wall of the shell 85 and which in practice, are closed by means of caps 10. Parts of the sleeves 9 are omitted and replaced by short glass tubes 13 so that when the carbons have been reduced to a certain length, this fact may be 75 ascertained by their upper ends appearing in the glass tubes. A cylindrical casing 14 secured to the sleeves 9 at their inner ends, incloses the protruding extremities of the electrodes between which the voltaic arc is 75 produced. The casing which is composed of an opaque substance, preferably metal, has two openings which are respectively in axial alinement with the lenses 4 and 5 and which are closed by means of caps 15 and 16 each 80 composed of a sheet of transparent or translucent material, such as glass or mica, set in a surrounding rim. The casing is furthermore provided with an opening opposite to that closed by the cap 15, which, in 85 case the shell has but one vertical lens as in the form shown in the drawings, is closed by a cap 17 composed of an opaque substance adapted to reflect the light, while when the lantern has two opposite vertical 90 lenses, as those used on board of ships, the cap 17 is constructed of transparent or translucent material the same as the others.

The caps 15 and 17 which close the openings in the sides of the casing 14 are removably held in place by nuts 21 screwed upon rods 19 which are pivotally mounted on the casing as at 20, and project through diametrically opposite slots in the edges of the caps. The nuts 21 are held in place by 100 means of springs 18 coiled around the rods 19 and bearing at their ends against the said nuts and against nuts 22 which are screwed upon the ends of the rods.

The regulating mechanism whereby the 105 electrodes are automatically re-adjusted to their proper distance during the period of illumination, comprises an electro-magnet

23, the vertically movable core 24 of which is pivotally suspended from a lever 25 which is fulcrumed upon a standard 26 mounted on a base 27 which is supported upon the bottom of the shell 2. A spring 28 connected at its ends to the short arm of the lever 25 and to a laterally projecting bracket 29 on the standard 26, is provided to maintain the lever, during de-energization of the magnet, in its normal position in which it engages an adjustable stop 30 on the standard 26. The long arm of the lever is pivotally connected with a tubular rod 31 which at its upper end, supports a metallic head 32 which has a tongue adapted to enter the interval between the ends of the electrodes during the period of their re-adjustment, and which in this operation, serves to provide by means of said tongue a stop which determines the normal length of the arc between the electrodes and completes the main operating circuit after the latter have been adjusted to their proper distance.

The rod 31 has a vertical reciprocating movement in a hollow standard 55 which is erected on the before-mentioned base 27 and it is rigidly connected with a cross-head 33 of non-conductive material, which at its ends carries the devices by means of which the electrodes are clutched in their adjusted position in the sleeves 9 while the lamp is in operation. These devices consist of levers 34 which are fulcrumed at the connected ends of bands 35 secured around the respective sleeves and which are adapted to frictionally engage with their short arms, the surfaces of the respective electrodes through openings in the sleeves 9. The long arms of the levers 34 are movably connected with rods 36 which are slidably mounted in bearings 37, lined with insulating bushings which form part of the cylindrical wall of the casing 14.

The lower portions of the rods 36 are threaded and project loosely through openings in the ends of the cross-head 33. Nuts 38 screwed upon the rods engage the upper surface of the cross-head while nuts 39 applied at the lower ends of the same, serve as abutments for springs 40 which are coiled around the rods to engage the lower surface of the cross-head.

When the reciprocating rod 31 is in its lowered position during the period of illumination of the lamp, the ends of the levers 34, are, by reason of the depressed position of the cross-head and through the instrumentality of the springs 40, maintained in frictional contact with the electrodes. When the rod 31 is subsequently moved upwardly, the springs 40 will maintain the clutch levers 34 in engagement with the electrodes until the head 32 at the end of the rod, has assumed its position between the electrodes, as shown in Fig. 4, and when the said rod is

again moved downwardly to withdraw the stop 32 from the said interval, the springs 40 will act to immediately move the levers 34 to the position in which they hold the electrodes against gravitational movement.

The lever 25 is connected at the end of its long arm with the vertically, sliding rod 41 of a circuit breaker 42 which controls the shunt circuit hereinafter to be described, and which consists of two flexible blades 43 secured at opposite sides of an insulating block 44, and respectively connected with the ends of a conductor 45 in a break in the said shunt circuit. A metallic cross-piece 46 at the end of the rod 41 is constructed to engage the contact blades 43 when the rod is in its lowered position.

The main operating circuit of the lamp includes a source of electricity 47 and conductors 48 and 49 which at their ends are connected with binding screws 50 secured around the electrode-sleeves 9, and the windings of the magnetic coil 23 are connected in the conductor 48 which is attached to the binding screw on the sleeve of the negative electrode. The hereinbefore-mentioned shunt circuit, designated by the numeral 45, includes a resistance coil 51, and one side of this circuit, in which the circuit-breaker 42 is disposed, is connected with the conductor 48 of the main circuit as at 52, while its other side has its terminal in the bifurcated extremity of a rod 53 which is fixedly secured in insulated relation to the casing 14 and whose ends straddle the lower portions of the electrodes 8 in spaced relation to the upper surfaces thereof, as is clearly shown in Fig. 7 of the drawings.

During the period of illumination when the points of the carbons 8 are at the proper distance from each other and the current passing through the lamp is at its normal voltage, the voltaic arc passing between the carbon points is naturally steady; the magnetic coil being energized, maintains its core in the retracted position, with the clutch levers 34 holding the electrodes immovable in the sleeves 9 and with the head 32 at the end of the reciprocating rod 31, in its lowered position, while the circuit breaker 42 in the shunt circuit is closed. The various parts remain in this position during the period of illumination until by burning away of the carbons, the arc between their extremities is lengthened to a predetermined extent or until the current becomes too weak by the irregularities in the strength and supply of the current in a circuit of this character, when the flame becoming unsteady, will arch and assume a higher position on the carbons with the result that the arc touches the bifurcated extremity of the terminal rod 53 and thus closes the shunt circuit which is normally open at this point.

The closing of the shunt circuit excludes

the magnetic coil 23 temporarily from the path of the current and the magnet being thus deënergized, causes the spring 28 to move the rod 31 upwardly through the instrumentation of the lever 25, until its head 32 has entered the interval between the carbon points, while by movement of the clutch levers, the electrodes are simultaneously released.

10 The electrodes impelled by gravity, move downwardly until they engage the stop 32 which determines the proper distance between its points and which being composed of conductive material, completes the main 15 circuit with the result that the magnet is again energized and the various parts of the regulating mechanism are restored to their original position.

By breaking the shunt circuit by means 20 of the circuit-breaker 42, the moment it has performed its function in temporarily excluding the electric magnet from the circuit, the flow of electricity through the lamp will, in case one or the other of the carbons is 25 missing either by accident or by being entirely consumed, be discontinued until the defect has been remedied.

It will be understood that the ohmage of 30 the resistance in the shunt circuit should at least be equal to the resistances of the normal arc and the magnetic coil and that inasmuch as it is the purpose of the resistance to prevent variations in the load on the dynamo or other source of electricity during 35 the readjustment of the electrodes, the same may be omitted in cases where the resistance is already included in the main operating circuit, as for example, the circuit of an electric tramway system.

40 The metallic casing 14 in which the flame is produced has been found to provide an effective substitute for the fragile glass globes heretofore employed, and while the mechanism shown and described is the best 45 at present known to me to effectively carry out the functions of my invention, I desire it understood that variations in their arrangement and construction may be availed of within the scope of the claims.

50 I claim—

1. In an arc lamp, a pair of convergent electrodes movable toward each other by gravity and connected in a main circuit, an electro-magnet in said circuit, a spring-controlled lever operatively connected with the 55 armature of the magnet, a vertically reciprocating device below the arcing ends of the electrodes connected with said lever and carrying a conductive stop adapted to enter the interval between the electrodes when the magnet is deënergized, clutch-levers adapted to clamp the electrodes in their adjusted positions, a cross-head connected with said device, rods on said cross head connected with said clutch levers so as to release the electrodes during movement of said stop into the interval, and means for effecting a temporary deënergization of the magnet when the normal condition of the voltaic arc is varied to a determinate extent.

2. In an arc lamp, a pair of convergent electrodes movable toward each other by gravity and connected in a main circuit, an electro-magnet in said circuit, a spring-controlled lever operatively connected with the 75 armature of the magnet, a vertically reciprocating device below the arcing ends of the electrodes connected with said lever and carrying a conductive stop adapted to enter the interval between the electrodes when the magnet is deënergized, clutch-levers adapted to clamp the electrodes in their adjusted positions, a cross head connected with said device, rods resiliently mounted on said cross-head and connected with said clutch-levers so as to release the electrodes during movement of said stop into the interval, and means for effecting a temporary deënergization of the magnet when the normal condition of the voltaic arc is varied to a determinate extent.

3. In an arc lamp, a pair of electrodes in a main circuit, an electro-magnet in said circuit, means normally holding said electrodes and adapted to operate for permitting a feeding movement of the same, a shunt-circuit having a terminal adjacent the interval between the electrodes and connected in a side of the main circuit, to be closed and thus temporarily exclude the 80 magnet from the path of the current when the normal condition of the voltaic arc is varied so as to establish an electric connection between said terminal and the other side of the main circuit, and means actuated by deënergization of the magnet for breaking the shunt-circuit.

35 In testimony whereof I have affixed my signature in presence of two witnesses.
